UNITED STATES PATENT OFFICE.

JESSE H. SROFE, OF KOKOMO, INDIANA.

DESIGN FOR A WIRE FENCE.

SPECIFICATION forming part of Design No. 30,420, dated March 28, 1899.

Application filed February 15, 1899. Serial No. 705,581. Term of patent 7 years.

To all whom it may concern:

Be it known that I, JESSE H. SROFE, a citizen of the United States, residing at Kokomo, in the county of Howard and State of Indiana, have invented and produced a new and useful Design for Wire Fences, of which the following is a specification.

In the accompanying drawing I have shown a side elevation of a wire fence presenting my design.

As shown in the drawing, the leading or more important features of my design consist in the fence having the several horizontal strands or wires A, B, C, D, and E, running longitudinally through the fence, and the double pickets F, having curved tops, which overlap or cross each other above the top strand or wire A and which have parallel portions f extending through the space between the strands or wires A and C, and the inclined

portions f', converging toward each other through the space between the strands or wires C and D, and the inclined portions f'', diverging from each other through the spaces between the strands or wires D and E, and the single pickets G, inserted between the double pickets F, so as to vertically bisect the diamond space formed by the converging and diverging portions f' and f'' of the double pickets, the whole presenting an attractive and ornate appearance, as shown in the drawing.

What I regard as new, and desire to secure by Letters Patent, is—

The design for a wire fence herein shown and described.

JESSE H. SROFE.
